(57) **CLAIM**

The ornamental design for a high-power hand-held laser for survival purposes, as shown and described.

DESCRIPTION

FIG. 1 is an isometric view of a high-power hand-held laser for survival purposes hereof, lined for the color blue.

FIG. 2 is a left elevational view of the high-power hand-held laser for survival purposes.

FIG. 3 is a front elevational view of the high-power hand-held laser for survival purposes, lined for the color blue.

FIG. 4 is a right elevational view of the high-power hand-held laser for survival purposes.

FIG. 5 is a back elevational view of the high-power hand-held laser for survival purposes.

FIG. 6 is an isometric view of another embodiment of the high-power hand-held laser for survival purposes, lined for the color red or pink.

FIG. 7 is a left elevational view of another embodiment of the high-power hand-held laser for survival purposes.

FIG. 8 is a front elevational view of a second embodiment of the high-power hand-held laser for survival purposes, lined for the color red or pink.

FIG. 9 is a right elevational view of a second embodiment of the high-power hand-held laser for survival purposes.

FIG. 10 is a back elevational view of a second embodiment of the high-power hand-held laser for survival purposes.

FIG. 11 is an isometric view of a third embodiment of the high-power hand-held laser for survival purposes, lined for the color violet or purple.

FIG. 12 is a left elevational view of a third embodiment of the high-power hand-held laser for survival purposes.

FIG. 13 is a front elevational view of a third embodiment of the high-power hand-held laser for survival purposes, lined for the color violet or purple.

FIG. 14 is a right elevational view of a third embodiment of the high-power hand-held laser for survival purposes.

FIG. 15 is a back elevational view of a third embodiment of the high-power hand-held laser for survival purposes.

FIG. 70 is a back elevational view of the high-power hand-held laser for survival purposes of FIG. 66.

FIG. 71 is an isometric view of a still further embodiment of a high-power hand-held laser for survival purposes, lined for the color violet or purple.

FIG. 72 is a left elevational view of the high-power hand-held laser for survival purposes of FIG. 71.

FIG. 73 is a front elevational view of the high-power hand-held laser for survival purposes of FIG. 71, lined for the color violet or purple.

FIG. 74 is a right elevational view of the high-power hand-held laser for survival purposes of FIG. 71.

FIG. 75 is a back elevational view of the high-power hand-held laser for survival purposes of FIG. 71.

FIG. 76 is an isometric view of yet another embodiment of the high-power hand-held laser for survival purposes, lined for the color yellow or gold.

FIG. 77 is a left elevational view of the high-power hand-held laser for survival purposes of FIG. 76.

FIG. 78 is a front elevational view of the high-power hand-held laser for survival purposes of FIG. 76, lined for the color yellow or gold.

FIG. 79 is a right elevational view of the high-power hand-held laser for survival purposes of FIG. 76.

FIG. 80 is a back elevational view of the high-power hand-held laser for survival purposes of FIG. 76.

FIG. 81 is an isometric view of yet still a further embodiment of the high-power hand-held laser for survival purposes, lined for the color green.

FIG. 82 is a left elevational view of the embodiment of the high-power hand-held laser for survival purposes of FIG. 81. FIG. 83 is a front elevational view of the high-power hand-held laser for survival purposes of FIG. 81, lined for the color green.

FIG. 84 is a right elevational view of the high-power hand-held laser for survival purposes of FIG. 81.

FIG. 85 is a back elevational view of the high-power hand-held laser for survival purposes of FIG. 81.

FIG. 86 is an isometric view of another embodiment of the high-power hand-held laser for survival purposes, lined for the color orange.

FIG. 87 is a left elevational view of the high-power hand-held laser for survival purposes of FIG. 86.

FIG. 88 is a front elevational view of the high-power hand-held laser for survival purposes of FIG. 86, lined for the color orange.

FIG. 89 is a right elevational view of the high-power hand-held laser for survival purposes of FIG. 86; and,

FIG. 90 is a back elevational view of the high-power hand-held laser for survival purposes of FIG. 86.

The device hereof is a hand-held laser device, which provides for generation and transmission of a laser therefrom.
